UNITED STATES PATENT OFFICE.

JAMES T. HUGHES, OF RANDOLPH, MISSOURI.

WINDOW-SIGN.

1,202,066.

Specification of Letters Patent. Patented Oct. 24 1916.

Application filed November 5, 1915. Serial No. 59,724.

To all whom it may concern:

Be it known that I, JAMES T. HUGHES, a citizen of the United States, residing at Randolph, in the county of Randolph and State of Missouri, have invented certain new and useful Improvements in Window-Signs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a window sign and more particularly to a sign for use in show windows, the principal object of the invention being to provide a device of this character which may be adjusted to fit windows of different width and may display advertising matter without detracting from the appearance of the window. In accomplishing this object I have provided improved details of structure, the preferred 25 forms of which are illustrated in the accompanying drawings, wherein:—

Figure I is an elevation of a window sign constructed according to my invention, the dotted lines indicating the extensibility of 30 the sign. Fig. II is a rear perspective view of the sign, illustrating its application to a show window.

Referring more in detail to the drawings: 1 and 1' designate rails of any suitable material but preferably of sheet metal, and having standards 2—2' extending upwardly at right angles from their outer ends, so that when the rails 1—1' are seated on a window sill the standards may extend upwardly 40 from the rail along and preferably in engagement with the opposite vertical members of a window frame. The rails 1—1' are independent of each other but their inner ends are adapted for connection through a keeper member 3, and preferably comprise a central portion 4 and end extensions 5—5', the end extensions having rearwardly extending, inverted troughed portions on their upper edges adapted for coöperation with a 45 troughed member on the lower edge of the keeper to form a guide from the rails so that the latter may be adjusted in the window by sliding the rails through the opposite ends of the keeper member.

50 The lower edge of the keeper is bent backwardly and upwardly to form the base 7 and

lip 7', and the upper edges of the end extensions similarly formed with the flanges 8 and depending lips 8', the width of the lips 7—8—8' being such that their free edges 55 will terminate closely adjacent each other when the keeper is formed and thereby provide a substantial guide for the rails, the spacing of the lips from the body part of the keeper being sufficient to allow the rails 60 to slide freely therein without lost motion.

Assuming the parts to be constructed and assembled as described, and with the front of the keeper, the rails and rail standards having suitable ornamental or advertising 65 matter, it is apparent that the separate rail members and keeper may be assembled in a relatively small space for storing or shipping. When the sign is to be arranged in a show window, the rails 1—1' are projected 70 into opposite ends of the guide and placed in the window, with the sides bearing advertising or display matter facing the outside 75 of the window, so that persons passing the window may view the same. The rails are 80 then moved outwardly until the edges of the standard abut against the vertical edges of the window frame.

When the parts have been adjusted with the standard contacting the frame and with 85 the panel of the keeper member at the center of the window, the standards are fixed in position by any suitable means, so that the sign will stand erect in the window and serve as a display or advertisement without 90 obstructing a larger window display that may be located back of the sign.

It is apparent that any suitable matter 95 may be displayed on the sign, in addition to the name of the proprietor of the store in whose window the sign is erected, and that because of the adjustability of the rail members in the keeper, the sign may be made in standard sizes for use in windows of different widths, thereby obviating the necessity 100 for the construction of a sign under given specifications for the window in which it is to be used.

Having thus described my invention, what I claim as new therein, and desire to secure 105 by Letters-Patent, is:

1. A window sign comprising base rails, having perpendicular end standards, and a keeper comprising a body portion having a troughed lower edge and inverted, trough-shaped members on its upper edge adjacent its ends, the part of the body portion be-

tween said inverted trough portions being extended upwardly to form a display panel between said end standards when the base rails are located in the guide way formed by the lower and upper troughed members, substantially as set forth.

2. A window sign comprising base rails, having perpendicular end standards, and a keeper comprising a body portion having a troughed lower edge and inverted trough-shaped members on its upper edge adjacent its ends, the part of the body portion between said inverted troughed portion being

extended upwardly to form a display panel between said end standards when the base 15 rails are located in the guide way formed by the lower and upper troughed members, the said base rails being slidably mounted in said guide way, to cooperate with the keeper to form an adjustable frame.

In testimony whereof I affix my signature in presence of two witnesses.

JAMES T. HUGHES.

Witnesses:

PHARES K. WEIS,
ARTHUR B. CHAMIEY.
